JOSIAH A. DEWEY, OF SAN FRANCISCO, CALIFORNIA, ASSIGNOR TO DEWEY DAVENPORT COMPANY, OF SAN FRANCISCO, CALIFORNIA, A CORPORATION OF CALIFORNIA.

SOFA-BED.

1,321,606.

Specification of Letters Patent. Patented Nov. 11, 1919.

Application filed November 8, 1916. Serial No. 130,109.

To all whom it may concern:

Be it known that I, JOSIAH A. DEWEY, a citizen of the United States, and a resident of the city and county of San Francisco, 5 State of California, have invented a new and useful Sofa-Bed, of which the following is a specification.

My invention relates to that type of folding bed generally known as the davenport 10 or sofa bed.

An object of my invention is to provide a sofa bed which in its folded position is capable of containing a full size upholstered mattress.

15 Another object of my invention is to provide a sofa bed in the folded position of which the mattress and bed frames are folded behind the seat.

The invention possesses other features of 20 advantage, some of which, with the foregoing, will be set forth in the following description of the preferred form of my invention which is illustrated in the drawings accompanying and forming part of the specification. It is to be understood that I do 25 not limit myself to the showing made by the said drawings and description, as I may adopt variations of the preferred form within the scope of my invention as set forth in 30 the claims.

Referring to the drawings:

Figure 1 is a cross section of the sofa bed when unfolded to form a bed. A portion of the upholstered mattress is broken away to 35 disclose the structure.

Fig. 2 is a cross section of the sofa bed when folded to form a sofa. The upholstered mattress is omitted to better disclose the structure.

40 Fig. 3 is a cross section of the sofa bed on a smaller scale showing the upholstered mattress in place.

My invention comprises a main frame or 45 stationary structure 4 in which a seat frame 5 is arranged. Preferably the seat frame is mounted on pivots 6 set in the stationary structure so that it can be turned up about the pivots to give access to a space 7 below the seat in which space, bed clothes are conveniently kept when the apparatus is closed. 50 The seat frame 5 is fitted with suitable upholstery 8 to provide a comfortable seat and the weight of the seat is carried by the piv-

ots 5 and the cross rail 12 which is part of the stationary structure.

Arranged behind the seat in an upright position is a bed frame section 14, Fig. 2, so mounted in the stationary structure that it may be moved into a horizontal position above the seat frame as shown in Fig. 1. The means for accomplishing this mounting include a curved arm 15 rigidly attached to the section 14. At its end the arm is attached by the pivotal connection 16 to the link 17 which in turn is mounted on the pivot 19 set in the stationary structure. The link 17 therefore carries the weight of the section 14. The pivot 16 conveniently may travel in arcs between the slats 5^a of the seat frame, and the rear wall 5^b of the 65 seat frame is suitably recessed to permit a free movement of the arms 15 as shown in Figs. 1 and 2; and it is obvious without specific illustration that the links 17 may be shortened a trifle so that the pivots 16 lie 70 below the plane of the slats and the curve of the arms 15 modified so that recessing of the rear wall 5^b is unnecessary. The placing of the pivots 16 below the seat frame rather than at the ends of the seat frame is of advantage since it saves valuable space at the ends of the seat frame. Means are provided 75 co-operating with the link 17 for controlling the position of the section at all points of its movement. A track or guide member 21 is disposed on each end of the stationary structure 4 and rollers 22 rotatably mounted near the lower edge of the section engage 80 a groove 24 formed in the tracks 21. As the section is moved from the upright to the 85 horizontal position about the movable pivot 16, the rollers 22 move upward in the tracks 21, thus definitely positioning the section at all times in respect of the stationary structure.

90 Foldably attached to the bed frame section 14 is a second section 26. Preferably a short section 27 is interposed between sections 14 and 26 so as to provide a space therebetween in which the upholstered mattress 28 may lie in the folded position of the parts. The mattress is preferably attached in any suitable way to the bed section frames or to the spring fabric 29, stretched in the frames. Stops 31 are provided on the 95 short section 27 so that the three sections 100 105

when unfolded are prevented from moving past the alined position shown in Fig. 1.

A stiffening rod 32 is connected to the sides of the section 27 to keep them from being displaced inwardly under the tension of the spring and the weight of the occupant of the bed. The rod is arched downwardly so as to carry it below the normal sagging of the spring and is pivotally attached to the sides of the section 27 on the outside, so that when the frames are folded as shown in Fig. 2, it lies about the upper edge of the frame 14.

A leg 33 is pivoted upon each side near the outer end of the section 26 to support the section when the bed is unfolded and the section is extended in line with the sections 14 and 27. Each leg is provided with an arm 34 having a hook 36 at the end, adapted to engage over a pin 37 fixed in an arm formed integral with the frame 14, when the frames are folded together as shown in Fig. 2. This engagement locks the two frames together inclosing the mattress 28 between them, producing in effect a single unit during the first stage of the unfolding movement and the last stage of the folding movement. A spring 38 suitably attached to the frame 26 and the arm 34 tends to hold the leg 33 in the extended position or the hook 36 in engagement with the pin 37, as the case may be.

Means are provided for supporting the section 14 in horizontal positon and thus keeping the extended sections in horizontal alinement therewith. For this purpose I prefer to make use of the back frame 41 of the sofa. The back frame is suitably upholstered to provide a comfortable back for the sofa and in the folded position effectively conceals the folding bed sections. At its lower end it is pivoted at 42 to an arm 43 formed integral with the frame 14. About this pivot it is allowed a limited motion by the links 44, one pivoted to each side of the frame at 45. Each link is formed with a slot 47 terminating in a notch 48. When the back frame is pulled outwardly the notch is engaged on a pin 51 set in the frame 14. This holds the back frame in the forward position indicated in the dotted lines 41^a of Fig. 2, and when the unit inclosing the mattress 28 is pulled forward into the horizontal position the back frame engages the pads 53 on the seat frame and forms a support for the frame 14. It is seen that in this construction sufficient space is left clear below the frame 14 to accommodate the normal amount of sag in the spring 29. A spring 54 attached to the link 44 tends to prevent its accidental disengagement from the pin 51.

The stationary structure is provided with a top board 55 and preferably this is hinged 65 at the rear so that it can be thrown up out

of the way to clear the back frame preparatory to opening the bed. Preferably a heavy coiled spring 57 is connected to the stationary structure and the section 14, whereby the weight of the section and attached folding members is largely balanced by the pull of the spring. The unfolding and folding movements are thus easily effected with but little effort on the part of the operator.

Assuming the sofa bed to be in the closed or folded position shown in Fig. 2; the top board 55 is first thrown back so that the top of the back frame 41 may be grasped and pulled forward into the position of the dotted lines 41^a. Continuing the outward pull, the unit comprising the locked folded frames inclosing the mattress swings upwardly about the movable pivot 16 to a horizontal position where it is supported by the combined effects of the rollers 22 engaging the tracks 21, the link 17 and the extended back frame 41 resting on the seat frame. The legs 33 are next lifted to disengage the hooks 36 and unlock the two frames 14 and 26. Frame 26 is then unfolded, moving together with the intermediate section 27 into horizontal alinement with section 14. The mattress 28 unfolds with the frames to which it is attached and the parts are then in position as shown in Fig. 1.

To fold up the structure, the frame 26 is turned over upon the frame 14 to inclose the mattress therebetween and the legs pulled down to lock the frames together into a single unit, which is then lifted by grasping the outer end of the back frame 41 and allowed to slip back into the upright position shown in Fig. 2. When the unit has nearly completed this movement, a pin 58 on the link 44 engages a curved ledge 59 on the stationary structure, riding up thereon and thereby releasing the link from the stop pin 51. This permits the back frame to move backwardly into its normal position. The top board 55 is next closed down and the parts are then in the folded position shown in Fig. 2, the frames resting against the stop 61.

I claim:

1. In a sofa bed, a stationary structure, a seat frame adapted to remain in fixed position on said stationary structure, a bed frame section slidably mounted on said stationary structure and connected thereto by a traveling pivot below said seat frame and adapted to move from a position behind said seat frame to a horizontal position, and a second bed frame section foldably arranged upon said first-named section.

2. In a sofa bed, a stationary structure, a seat frame arranged on a fixed pivot in said stationary structure, a track on said stationary structure, a bed frame section slidably arranged on said track and a traveling pivot which is always below the seat

frame, whereby said section is movable from a position behind said seat frame to a horizontal position, and a second bed frame section foldably arranged upon said first 5 named section.

3. In a sofa bed, a stationary structure, a seat frame arranged in said stationary structure, a track on said stationary structure, a bed frame section slidably arranged on said track, an arm extending from said section to a point always below said seat frame and a link pivoted to said stationary structure and to said arm, said section being adapted to move on said track 10 and link from a position behind said seat frame to a position above said seat frame.

4. In a sofa bed, a stationary structure, a seat frame arranged upon a fixed pivot in said stationary structure, a bed frame section arranged on a traveling pivot which is always below said seat frame and adapted to move from a position behind said seat frame to a horizontal position, a second bed frame section foldably arranged upon said 20 first named section and an upholstered mattress arranged upon said sections.

5. In a sofa bed, a seat frame, a bed frame section adapted to move from a position behind said seat frame to a horizontal 30 position above said seat frame, a back frame pivoted upon said section, and means for holding said back frame in extended posi-

tion upon said section to support said section upon said seat frame.

6. In a sofa bed, a stationary structure, a seat frame arranged in said stationary structure, a track on said stationary structure, foldable bed frame sections slidably arranged on said track, and means extending below said seat frame when said bed sections are folded and extending around the rear edge of the seat frame when said bed sections are unfolded for further connecting said bed sections to said stationary structure. 45

7. In a sofa bed, a stationary structure, a seat frame arranged in said stationary structure, a track on said stationary structure, a bed frame section slidably arranged on said track and adapted to move from a 50 position behind said seat frame to a horizontal position, and means operatively connecting said stationary structure to said bed section and extending below said seat frame when said bed section is behind the seat 55 frame, and extending around the rear edge of the seat frame when the bed section is in horizontal position.

In testimony whereof, I have hereunto set my hand at San Francisco, California, this 60 2d day of November, 1916.

JOSIAH A. DEWEY.
